UNITED STATES PATENT OFFICE

ZACK COLWELL, OF NILES, OHIO

METHOD FOR MANUFACTURING INGOTS

Application filed March 7, 1930. Serial No. 434,031.

This invention is predicated upon a novel and unique conception involving a practical and feasible method and physical means for producing metal ingots, such as are employed in the manufacture of steel.

The improved method, which is believed to be original, embodies an unusually efficient process for increasing the efficiency of steel ingots by preventing the objectionable piping action which ordinarily accompanies the construction of ingots of this character.

The physical means which is intimately allied with the method of production, embodies the utilization of a new type of ladle expressly designed for insuring efficient and effective accomplishment of the desired result of the invention.

The factors of novelty, utility and invention constituting the fundamental factors of this new inventive conception will become more readily apparent from the following description and drawings.

In the drawings:

Figure 1 is a top plan view of the especially constructed ladle constituting the mechanical part of the conception.

Figure 2 is a vertical sectional view with portions broken away and shown in elevation.

I will first describe the ladle. This is generally designated by the numeral 3. It comprises a receptacle of appropriate proportion such as is generally employed for containing the molten metal. In accordance with the present invention, there is a vertical web or partition 4 formed on the interior and extending from the bottom to the top. This is here shown of arcuate configuration and it serves to define a main chamber or compartment 5 for reception of the molten metal, and a companion chamber or compartment 6 for collection and reception of the hot slag.

It will be noted that the upper edge of the partition is formed with a notch 7 which defines an overflow passage allowing the rising hot slag to overflow from the main chamber 5 to the subordinate hot slag chamber 6. There is an upstanding nipple 8 in the bottom of the chamber 5 defining the outlet for the molten metal. This is arranged near the

wall of the main receptacle as shown in Figure 1.

The plug valve 9 which cooperates with the outlet is mounted on an operating frame 10 which is manipulated by appropriate means (not shown). There is a similar nipple 11 formed in the compartment 6 which serves to discharge the hot slag and a plug valve 12 co-operates with this, the valve being operated through the medium of the actuating frame 13.

It is a matter of common knowledge to persons skilled in the art to which the invention relates that when the metal is taken from the furnace and poured into the ladle it contains slag, which rises to the top of the ladle. In the present ladle it will be noted that there is a notch or passage 7 in the top of the partition 4 which allows the slag from the surface of the hot metal to run from the compartment 5 over into the compartment 6 where it accumulates, thus automatically placing slag in this part of the container to be used to cap the ingots.

The improved process or method involves the improvement of steel ingots by preventing piping as before mentioned. This is accomplished by capping the steel ingots with hot slag. Particular emphasis is to be laid on this result. The effect is thus. By capping the ingots with hot slag the heat in the steel in the top of the ingots is retained in a molten condition, permitting the same to flow into any cavity that may be made by escaping gas, and in so doing, preventing what is commonly known as piping of ingots.

The method of operation is as follows:

The ladle is placed about six feet above the ground and under it is a narrow gauge of railroad track, over which the ingot molds, for casting purpose, are hauled. When a mold is under the stopper or outlet 8, and the plug 9 is raised, the molten metal is allowed to flow into the mold beneath it until practically filled. The mold is then moved so as to be directly under the outlet indicated at 11. This permits the discharging of slag, and a sufficient amount of slag is allowed to flow through this into the mold to fill the remaining portion thereof.

These outlets are spaced distances apart equal to the distance between the ingot molds on the cars running beneath the ladle, which means that as one ingot is being capped with 5 slag, the ingot mold next behind can be filled with molten metal, thus performing both operations simultaneously and in quick succession. This minimizes labor and expedites the casting operation.

- 10 There is unusual continuity of action between the physical means and the method which enables this practical inventive conception to be carried into actual practice. This will be appreciated by persons familiar 15 with the art to which the invention relates. Therefore, a more lengthy description is regarded as unnecessary.

Minor changes in shape, size, and rearrangement of details coming within the field 20 of invention claimed may be resorted to in actual practice if desired.

I claim:

1. The method of constructing steel ingots 25 consisting of suspending a duplex ladle above a series of mobile molds, filling said duplex ladle with furnace run until the slag rises and overflows into a slag retaining means thereon, discharging the steel first into an ingot mold and filling said mold almost full, 30 and secondly, discharging hot slag from said slag retaining means into the same mold for capping the steel, and discharging steel into the next adjacent mold while simultaneously so capping the steel in the preceding mold 35 with slag, whereby to produce simultaneous action of filling and capping two molds at a time.

2. A method of casting steel ingots as described comprising pouring the furnace run 40 into a duplex ladle having means for separating the slag from the steel and retaining the slag separate from the steel, and valving first a quantity of steel into a mold and while capping another by valving a quantity of 45 slag thereon from the same ladle.

3. A method of casting steel ingots as described comprising filling a duplex ladle with molten furnace run until the slag rises therein and overflows into a slag retaining means 50 thereon, and then valving the steel into a mold and capping another mold with slag valved from said retaining means.

4. A method of pouring and capping steel ingots comprising pouring furnace steel into a 55 ladle until the slag rises in the ladle and overflows into a separate slag retaining compartment in said ladle, the ladle arranged to straddle a pair of molds movable into position thereunder, then simultaneously pouring steel and slag from the ladle to fill an empty mold and to cap a filled mold with slag.

5. A method of pouring and capping steel ingots comprising pouring furnace steel into 60 a ladle suspended over a movable series of

ingot molds so as to cause the slag to rise in the ladle and overflow into a separate compartment in the ladle, then moving a pair of molds into position under said ladle and simultaneously filling one of the molds and 65 capping the other.

In testimony whereof I affix my signature.
ZACK COLWELL.
